UNITED STATES PATENT OFFICE.

GEORGE C. AVERY, OF LOUISVILLE, KENTUCKY.

BENDING PLOW-HANDLES.

SPECIFICATION forming part of Letters Patent No. 252,712, dated January 24, 1882.

Application filed June 23, 1881. (No model.)

To all whom it may concern:

Be it known that I, GEORGE C. AVERY, of Louisville, in the county of Jefferson and State of Kentucky, have invented certain Improvements in the Art of and Means for Bending Wood for Plow-Handles, &c.; and I do hereby declare that the following is a full and exact description thereof, reference being had to the accompanying drawings, making part of this application:

My invention relates to certain new and useful improvements in the art of making plow-handles and other articles of bent wood, and in the means or devices employed for holding the bent portion of the wooden article during the usual and requisite time for the wood to set.

Previous to my invention it has been customary in the art of forming the curved end portions of plow-handles to bend such portion from a straight stick (after having subjected the wood to the proper steaming process to render the stick sufficiently pliable) over a former, and then fasten or hold the wood in this bent condition after its removal from the bending-machine (usually for about thirty-six hours, by means of a tie-rod or equivalent device operating to tie together one end of the curved or bent part and the straight part of the stick. This mode of practicing the art is well known to those familiar with the manufacture of wooden plow-handles and analogous articles. In this method of practicing the art of making such articles the serious difficulty 35 occurs of a rupturing or upsetting of the fibers of the wood at that portion of the handle in the vicinity of the point where the curve runs into the straight part of the stick, and this difficulty results in such a defective article of manufacture that a large percentage of the bent sticks are too imperfect for the market, and have to be condemned after the bending and curving processes have been performed. This of course necessarily adds largely to final 45 cost of manufacture of the completed and perfect articles, and hence any improvement by which this destruction of or injury to the fibers of the wood by the bending process is overcome must be of great advantage.

I have found by experiment and practice that the injury resulting to the bent wood arises from the practice of tying the end of

the sharply curved portion of the stick to the straight part, so that, instead of permitting the tie-rod to perform the function of tying together the ends of the curve, so to speak, said tie-rod is caused to produce a pushing action of the straight part of the stick against the bent part where the curve runs out the straight part, thus inducing to a sort of upsetting action of the particles of the wood, which, having its grain or fibers running lengthwise of the stick, is ruptured at the locality before alluded to; and I have found that by bracing or tying together the ends of the curve 60 this serious difficulty is perfectly overcome.

My invention therefore consists, in the first place, as an improvement in the art in tying together the extremities of the curved or bent portion of the stick, thus inducing the tie-rod 70 or equivalent device employed to act upon the principle of a chord to the arc of the curved part of the wood, and to operate in a manner analogous to that of a bow-string, distributing the bending strain on the fibers of the stick 75 about equally throughout the portions extending from the middle to the ends of the bent part.

My invention further consists in means for carrying out this method of tying up the bend, 80 the said means being essentially a suitable brace, cord, or tie-rod, combined with the usual spring-plate, which is applied to the exterior of the curved part of the stick and clamped to the straight part of the latter.

To enable those skilled in the art to practice my invention, I will now proceed to more fully explain the several features thereof, referring by letters to the accompanying drawings, which form part of this specification, and in which— 85

Figure 1 is a side elevation of a bent plow-handle bar or stick bent by the usual means, but having its curved part tied up, ready for the curing and setting process, according to the method made the subject of the first part 95 of my invention and by the means made the subject-matter of the second part of my invention. Fig. 2 is a view looking at the under side of the contrivance seen at Fig. 1, and Fig. 3 is a cross vertical section at the line xx of Fig. 1. 100

In the several figures the same part will be found designated by the same letter of reference.

In the contrivance shown for holding the

bent stick the construction is such as to adapt it to hold two sticks at once. This form is not, however, essential to any part of the invention made the subject of this application, and 5 will be found more particularly described in another filed by me, in which this construction of the holder and certain improvements in the machinery for bending are claimed.

A and B represent two plow-handle ends, 10 which have been bent in the usual manner, and to which has been applied during the bending process a spring-plate, C, provided at one end with a cast-iron shoe, D, against the inner surface of which abut and rest the ends of the 15 sticks A and B, as shown. To the other end of the spring-plate C is securely fastened a casting, E, to the upper ear-pieces, e, of which is pivoted the upper end of a link, F, and to the lower lugs, f, of which is pivoted the upper 20 end of the tie-rod G.

To the lower end of the link F is pivoted a 25 clamping-plate, H, while from the lower end of the tie-rod G project laterally pins h, adapted to engage with the flange-like projections i i of the cast-metal shoe D, all as clearly illustrated.

J represents wedges, which may be driven 30 in between the plate H and the lower surface of the sticks or wooden bars, for the purpose of effecting the retention of the plate H in proper 35 place and the confinement securely of the bars A B between said plate and the casting E.

It will be seen that the curve of the stick A runs substantially from the point 1 to the point 2, and that the tie-rod G is in a position to 35 form practically the chord to the arc 12. By thus tying together the ends of the curve of the bent wood (instead of tying the point 2 to the remote extremity of or to some other point in the straight part of the stick, as has heretofore 40 been the custom) I find by a thorough practical test that instead of seven and one-half per cent. of the bent sticks being defective at about the point marked x at Fig. 1, and seven per 45 cent. of the bent sticks being unfit for use, not more than one in every hundred has any im-

perfection in the bend. After the placement of the stick in the holder contrivance, with its end against the plate D and its body between plates E and H, the plate H is struck with a hammer and driven in a direction indicated by 50 the arrow at Fig. 1. The stick and holder-spring C are then bent, and the tie-rod having had its lugs h caught onto the projections i, as shown, the stick and holder are put one side for the usual curing or setting process. 55 Any tendency of the lower end of the bent bar (and the spring-plate C) to spring outward will exert a strain longitudinally on the tie-rod G, that will operate to make said tie-rod pull the plate E in the direction indicated by the 60 arrow at Fig. 1, and any such movement of said plate must of course operate to bind or clamp the sticks A B more rigidly between said plate and that marked H.

What I claim in this application as new, and 65 desire to secure by Letters Patent, is—

1. As an improvement in the art, holding in place the bent portion of the stick or bar by tying together the ends of the curve or curved portion of the stock, in substantially the manner described.

2. As a novel contrivance for tying up the bent stock during the usual setting and curing process, the spring-plate C, provided at one end with a device for the end of the stick 75 to bear against and at the other end with a slotted bearing-plate, E, in combination with a tie-rod, G, pivoted centrally to said plate and adapted to engage with the device against which the stick end bears, and a clamping- 80 plate, H, and centrally-arranged link-bar F, pivoted at its ends to said plates E and H, all substantially in the manner specified, for the purposes set forth.

In witness whereof I have hereunto set my 85 hand this 23d day of June, 1881.

GEORGE C. AVERY.

In presence of—

W. G. WIGGINTON,
HENRY H. McDougall.
